UNITED STATES PATENT OFFICE.

HERBERT CHAMPION HARRISON, OF LOCKPORT, NEW YORK, ASSIGNOR TO HARRISON MANUFACTURING COMPANY, INC., OF LOCKPORT, NEW YORK, A CORPORATION OF NEW YORK.

HEXAGONAL CONSTRUCTION OF RADIATOR-CELLS.

1,076,364.

Specification of Letters Patent.

Patented Oct. 21, 1913.

Application filed November 1, 1912. Serial No. 729,118.

To all whom it may concern:

Be it known that I, HERBERT CHAMPION HARRISON, a subject of the King of Great Britain, residing at Lockport, in the county of Niagara and State of New York, have invented certain new and useful Improvements in Hexagonal Construction of Radiator-Cells; and I do hereby declare the following to be a full, clear, and exact description of the invention, such as will enable others skilled in the art to which it appertains to make and use the same.

This invention relates to radiators having air cells of a hexagonal shape, and has for its purpose to produce a radiator which will be simple in construction, efficient in action, and one which will have longer water passages, and therefore be more efficient in cooling the water than those heretofore proposed.

To these ends the invention consists in the novel details of construction and combinations of parts more fully hereinafter disclosed and particularly pointed out in the claims.

Referring to the accompanying drawings forming a part of this specification, in which like numerals designate like parts in all the views:—Figure 1 is an elevational view partly in section of a radiator built in accordance with my invention; Fig. 2 is a perspective view partly in section of a portion of the air cells showing the water courses therebetween; and Fig. 3 is an enlarged end elevational view, partly in section, of a plurality of air cells, also showing a water course therebetween.

1 indicates the usual framework of a radiator, 2 the usual water chamber provided 40 with a bottom plate 3 having the water passages 4 through which the water enters the zig-zag passages 5 between the hexagonal shaped cells 6 of which the main body of the radiator is composed. In some well known 45 forms of construction, however, the top and bottom plates 3 may be dispensed with.

In producing my hexagonal cells, I take a thin strip of metal and fold it upon itself a plurality of times to form the plaits 8 and 50 bend the metal at the point 9 outwardly as it leaves one end of the plait 8 at an angle of 120° to said plait, while at a distance equal to the length of the plait 8 and at the point 10, I bend the metal again inwardly 55 and at an angle of 120° to itself. I next, at

the point 11, equal to another distance of the length of the plait 8, preferably indent the metal as shown, and again bend the same outwardly at an angle of 120° to itself, and finally, at the point 12, equal to 60 the distance of the length of the plait 8, I further bend the metal inwardly at 120° to itself. At the point 13, equal to the length of the plait 8, I next form a second plait 8 and repeat the foregoing operations until a 65 strip of sufficient length is produced. I next place two such strips together, the plaits 8 and 14 of the respective strips occupying staggered relations to each other, and mutually fitting the indents 11 of their 70 coacting plates as shown. When two such plates are thus associated together, the hexagonal cells 16 are produced, and the ends 17 of some of the plates are finished off, as by bending them inwardly to form a flat surface; while the other ends 18 of other plates are finished off, as by cutting the metal at a plait on one plate, and at an indent 15 on the other plate, in order to form another 75 flat surface. After a series of cells are thus produced to form a radiator unit, a plurality of such units are brought together, as indicated in Fig. 3, the flat surfaces just described being secured to the plate 3, as by solder or otherwise, the zigzag water 80 passages 5 being left between the vertical rows of cells 16, as shown. It will be observed that by thus securing a plurality of cellular units together, an entire radiator section provided with zigzag water courses is 85 readily produced, and that a plurality of sections make up the radiator in the usual way. It will further be observed that the units when made are self-aligning in assembling 90 owing to their peculiar shape. In addition 95 to the above, an exceedingly strong structure may be made out of very thin material owing to the indentations 15 forming a firm support for the plaits 8 and 14, and thereby permitting the cell walls to be firmly 100 braced. It is an important feature of this invention that the zigzag water courses 5 thus produced are necessarily longer than any straight water courses between the same 105 cells could possibly be, and that therefore the water is subjected to a greater cooling action than could otherwise be the case.

It is obvious that those skilled in the art may vary the details of constructions, as well as the arrangement of parts without 110

departing from the spirit of my invention, and therefore I do not wish to be limited to the above disclosure except as may be required by the claims.

5. What I claim is:—

1. In radiators the combination of a plate bent on itself to form a plait, then bent outwardly and inwardly a plurality of times whereupon it is again bent upon itself to 10 form a second plait; a second plate provided with bends and plaits similar to the first plate and having its plaits located in a staggered relation to the first mentioned plaits to form a plurality of polygonal cells; 15 and means for securing said plates together, substantially as described.

2. In radiators the combination of a plate bent on itself to form a plait, then bent outwardly and inwardly a plurality of times whereupon it is again bent upon itself to 20 form a second plait, said plate also provided with indentations between contiguous plaits; a second plate provided with bends, indentations and plaits similar to the first plate 25 and having its plaits located in a staggered relation to the first mentioned plaits and entering the indentations in said first mentioned plate to form a plurality of polygonal cells; and means for securing said plates 30 together, substantially as described.

3. In a radiator, the combination of a plurality of cell units comprising a pair of oppositely disposed plates folded to form a series of plaits and secured together with 35 said plaits of the respective plates extending in staggered relation to partition the space between said plates into a row of polygonal cells, the cells of one unit having pro-

jecting portions adapted to coact with retreating portions between adjoining cells in 40 the other unit to form a zig-zag water course; and means for securing said units in a spaced relation so as to form said water course, substantially as described.

4. In a radiator the combination of a pair 45 of oppositely disposed plates so bent and located relatively to each other as to form a row of hexagonal cells separated by integral plaits extending alternately from the respective plates, the end of one of said 50 plates bent inwardly to form a flat surface, and a supporting plate secured to said inwardly bent ends, substantially as described.

5. In a radiator the combination of a plurality of cell units comprising a pair of oppositely disposed plates so bent and located 55 relatively to each other as to form a row of hexagonal cells separated by integral plaits extending alternately from the respective plates, the end of one of said plates bent inwardly to form a flat surface, and the said units being so located and spaced relatively 60 to each other that the outwardly projecting angles of the cells in the one unit will be opposite the retreating angles between adjacent cells in the other unit to form a zig-zag water course, and a supporting plate secured to said inwardly bent ends, substantially as described.

In testimony whereof, I affix my signature, 70 in presence of two witnesses.

HERBERT CHAMPION HARRISON.
